(57) **CLAIM**

The ornamental design for a kick scooter, as shown and described.

DESCRIPTION

FIG. 1 is a first perspective view of a kick scooter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG.

1;

FIG. 10 is an enlarged view of the selected portion 10 in FIG. 2; and,

FIG. 11 is an enlarged view of the selected portion 11 in FIG.

2.

The dash-dot broken lines are included to annotate partial views in FIGS. 1, 2 and 9-11. All other broken lines represent portions of the kick scooter that form no part of the claimed design. None of the broken lines form a part of the claim.
